UNITED STATES PATENT OFFICE.

ARTHUR J. TOWNSEND, OF CANTON, OHIO.

ROLLING-MILL REPEATER.

1,343,652.

Specification of Letters Patent. Patented June 15, 1920.

Application filed May 7, 1918. Serial No. 233,024.

To all whom it may concern:

Be it known that I, ARTHUR J. TOWNSEND, a citizen of the United States, residing at Canton, in the county of Stark and State 5 of Ohio, have invented certain new and useful Improvements in Rolling-Mill Repeaters, of which the following is a specification.

The invention relates to repeating mechanism for use in returning hot or cold metal strips or thin plates from one pass of a duo mill or a double stand of rolls, and entering them into the reverse pass of the same mill; and the object of the improvement is to provide means which will accomplish this work with a positive action in such a manner as will carry the strip in tension to prevent a buckling from the first pass and will facilitate the process of finishing the strips 20 so that the same can be accomplished without a reheating thereof.

The objects of the invention thus outlined in general terms, and ancillary advantages, are attained by the embodiment thereof 25 illustrated in the accompanying drawings forming part hereof, in which—

Figure 1 is a longitudinal elevation section of a duo mill and the repeater;

Fig. 2, a side elevation of the repeater; 30 Fig. 3, a plan view of the repeater; and Fig. 4, a transverse section of the repeater on line 4—4, Figs. 2 and 3.

Similar numerals refer to similar parts throughout the drawings.

The ordinary duo mill 1, shown in Fig. 1 of the drawings, is located at the delivery end of a roller chute or table 2 which carries the long strips or plates from a roughing mill or universal rolls, not shown, which 40 reduce the strips from heated slabs in the usual manner.

The lower rolls 3 of the duo mill usually make the first or forward pass and the upper rolls 4 usually make the second or return pass, from which upper rolls the strips are returned to the chute or table 2 whence they are delivered by a lateral transfer to another roller table which carries the strips forward again to a bull head or final finishing mill not shown, which may be and preferably is located alongside the duo mill. Suitable guideways 5, 5^a, 6 and 6^a are provided for carrying the strips respectively

from the table 2 to the rolls 3, and returning the strips from the rolls 4 to the table 2. 55

The repeater 7 is located some fifteen feet in rear of the mill and is composed of suitable housings 8 carrying journal bearings for the shaft 9 for the main drum 10 for the shaft 11 for the sprocket wheels 12 located 60 directly above the drum, for the shaft 13 for the pulley wheels 14 located below the forward side of the drum, and for the shaft 15 for the pulley drum 16 located a substantial distance in rear of the main drum. 65

The drums 10 and 16 are preferably provided with peripheral flanges 17 and 18 on each edge, between which flanges the width of the face of the drum exceeds the greatest width of strips to be operated upon; and a sufficient number of sprocket wheels 12 and pulley wheels 14 are located side by side, to substantially correspond to the width of the drums. 70

A series of laterally adjacent sprocket 75 chains 19 are mounted around the rear sides of the drums 10 and 16 and around the forward sides of the wheels 12 and 14, as shown in Figs. 1 and 2, and the arrangement of the parts and the suspended weight of the 80 belt formed by these chains between the wheels and the pulley drum cause the half to press in a clamping embrace around substantially the entire rear half of the main drum. 85

A pulley wheel 20 is provided on the sprocket wheel shaft 11 and power from a suitable source as the motor 21 is transmitted thereto by a belt 22, by means of which the repeater is preferably operated 90 independently of the mill, although it may be geared thereto if desired.

Guide ways 23, 23^a 23^b and 23^c are provided to carry the strips from the lower rolls 3 of the mill to pass upon the chains 95 below the drum, and suitable guideways 24 and 25 are provided to carry the strips upon the return from the upper side of the main drum to the upper rolls 4 of the mill; and the speed of the repeater is so related to the 100 speed of the mill that the chains passing around the main drum will travel slightly faster than the periphery of the lower rolls of the mill. By means of this differential speed, the action of the repeater carries the 105 strip in tension from the lower rolls to the

main drum and prevents any buckling thereof in passing from the mill to the repeater, it being understood that there may be a slight slipping of the sheet in traveling between the chains and the main drum to compensate for this differential speed.

In the operation of the mill and the repeater, in the direction shown by arrows in Fig. 1, when strips make the first pass 10 through the lower rolls 3 of the mill, they are directed by the corresponding guideways into the lower nip of the main drum and chains, the operation of which carries the advancing end of the strip upward and 15 forward over the top of the drum whence the strip is directed by the upper guideways, head first into the nip of the upper rolls 4 of the mill, the peripheral speed of which does not exceed and may be slightly slower 20 than that of the lower rolls, and such fullness as there may be in the length of the strip occurs between the repeater and the return rolls, where the same is negligible.

It will be understood that the chains of the 25 lateral series 19 are spaced closely together and cover substantially the entire width of the face of the main drum, so that strips of varying widths can be handled by the repeater, and in all cases, the entire width of 30 the strip is subject to the embracing and gripping action of the chains upon the drum, which action extends around nearly the entire rear half of the drum. The repeater

thus described is specially well adapted to handle strips running from 80 to 90 feet in 33 length and return them for the second pass through the duo mill so as to be transferred and finished in the bull head mill by the single initial heat of the ingot; thus completely finishing the strips without a re- 40 heat and also by apparatus of less length than otherwise required.

I claim:—

1. The combination of a double stand of 45 rolls, a repeater mechanism in rear of the rolls, guideways between the respective rolls and the repeater mechanism, and means for operating the repeater mechanism slightly faster than the lower rolls to carry sheet strips in tension from said lower rolls. 50

2. A rolling mill repeater comprising a drum having peripheral flanges on its ends, a sprocket wheel above, a pulley wheel below and a pulley drum in rear of the drum, and 55 endless chains operating on the sprocket and pulley wheels in clamping embrace around the rear side of the drum.

3. A rolling mill repeater, comprising a rotatable drum, a sprocket wheel above, a pulley wheel below and a pulley drum in 60 rear of the drum, endless chains operating on the sprocket and pulley wheels in clamping embrace around the rear side of the drum.

ARTHUR J. TOWNSEND.
